UNITED STATES PATENT OFFICE.

MATHEW J. WEBER, OF COLUMBUS, OHIO, ASSIGNOR TO THE OHIO PUMP & BRASS COMPANY, OF COLUMBUS, OHIO.

MOTOR.

1,149,549.

Specification of Letters Patent. Patented Aug. 10, 1915.

Application filed September 26, 1914. Serial No. 863,749.

To all whom it may concern:

Be it known that I, MATHEW J. WEBER, a citizen of the United States, residing at Columbus, in the county of Franklin and State 5 of Ohio, have invented certain new and useful Improvements in Motors; and I do hereby declare the following to be a full, clear, and exact description of the invention, such as will enable others skilled in the art to 10 which it appertains to make and use the same.

This invention relates to improvements in motors and more particularly to such as are adaptable for use in driving the agitator 15 shaft of a washing machine,—one object of the invention being to provide simple and efficient means whereby motion may be transmitted, with a minimum of lost motion and frictional resistance, from the piston 20 tons of a fluid pressure motor to a shaft for oscillating the latter.

With this and other objects in view the invention consists in certain novel features of construction and combinations of parts as 25 hereinafter set forth and pointed out in the claims.

In the accompanying drawings, Figure 1 is a plan view showing the application of my improvements, and Fig. 2 is a sectional 30 view.

1 represents a base plate which may be secured upon a washing or other machine, in any suitable manner. A straight fluid pressure motor 2 is mounted upon the base plate 35 and provided with suitable valve mechanism to cause the pistons to reciprocate when fluid pressure (such as water pressure) is admitted. The specific construction of the valve mechanism does not constitute a part 40 of my present invention and need not, therefore, be specifically described and shown.

Posts 3, 3, are located at respective ends of the base plate 1 at one side of the motor 2 and constitute supports for a sliding yoke 4, which may be conveniently made of malleable iron. The posts 3 are provided at their free ends with projections 5 on which guide rollers 6 for the yoke are mounted. The arms of the yoke are rigidly secured to 50 the rods 7 of the respective motor pistons, and centrally between its ends, said yoke is provided with a slot 8 and with lugs 9 above and below said slot.

The base plate 1 is made with an extension 55 10, and said extension has rigid there-

with, a bearing sleeve 11 for a shaft 12, said bearing sleeve projecting both above and below the base plate.

The shaft 12 may be connected with the agitator or other moving part of a washing 60 or other machine (not shown), and is provided at its upper end with a crank arm 13 having a wrist pin 14.

In rear of the bearing sleeve 11 and spaced a short distance therefrom, is a post 15 65 having a pin or projection 16 at its free end.

One end of a link or lever 17 enters the slot 8 of the yoke 4 and is pivotally connected between the lugs 9. The link or lever 17 is made with two elongated slots 18—19 70 and projects laterally from the yoke over the bearing sleeve 11 and post 15, the latter serving as a bearing for said link or lever. The slot 18 of the lever 17 receives a phosphor-bronze slide block or bearing 20 which 75 is mounted loosely upon the pin or projection 16 of post 15, while the longer slot 19 of said lever receives a phosphor-bronze slide block or bearing 21 mounted loosely on the wrist pin 14 of the crank shaft. 80

It is apparent that when the yoke 4 is reciprocated by the action of the motor, oscillatory motion will be imparted to the lever 17, the phosphor-bronze bearing block 20 at the upper end of the post 15 constituting a fulcrum on which the lever moves, while the connection of said lever with the crank shaft through the medium of the phosphor-bronze slide block 21 will cause 85 said crank shaft to be oscillated. 90

Slight changes might be made in the details of construction of my invention without departing from the spirit thereof or limiting its scope and hence I do not wish to restrict myself to the precise details 95 herein set forth.

Having fully described my invention what I claim as new and desire to secure by Letters-Patent, is:

1. The combination with a reciprocating 100 motor and a crank shaft, of a yoke secured to the piston rod of the motor, a lever connected with said yoke, a slide bearing connecting said lever with the crank shaft, and a slide bearing fulcrum for said lever. 105

2. The combination with a motor having piston rod projecting from respective ends thereof, of a yoke rigidly secured to said piston rods, a crank shaft, a slotted lever pivoted to the yoke, a fulcrum post with 110

- which said lever is slidingly and pivotally connected, and a bearing block loosely mounted on the wrist pin of the crank shaft and movable in the slotted lever.
- 5 3. The combination with a motor having piston rods projecting from respective ends thereof, of a yoke connecting said piston rods, a crank shaft provided with a wrist pin, a fulcrum post having a pin, a slotted lever pivoted to the yoke and movable on said fulcrum post, a bearing block on the pin of the fulcrum post and disposed in the slotted lever, and a bearing block mounted on the wrist pin of the crank shaft and disposed in said slotted lever.
- 10 4. The combination with a motor having piston rods projecting from respective ends thereof, and a crank shaft having a wrist pin, of a yoke connecting said piston rods, said yoke having a slot intermediate of its ends, a lever pivotally connected to the
- 15
- 20

slotted portion of the yoke, a fulcrum post on which said lever is normally mounted, and connections between an intermediate portion of said lever and the wrist pin of the crank shaft.

5. The combination with a motor, of a yoke connected with the same, a fulcrum post, a crank shaft between the fulcrum post and the yoke and having a wrist pin, a slotted lever pivoted to the yoke, a phosphor-bronze slide bearing mounted on the fulcrum post and in said slotted lever, and a phosphor-bronze slide bearing mounted on the wrist pin and in said slotted lever.

35 In testimony whereof, I have signed this specification in the presence of two subscribing witnesses.

MATHEW J. WEBER.
